(57) CLAIM

The ornamental design for a chair control housing, as shown and described.

DESCRIPTION

FIG. 1 is a left side perspective view of the chair control housing;

FIG. 2 is a bottom view of the chair control housing of FIG. 1;

FIG. 3 is a right side view of the chair control housing of FIG. 1;

FIG. 4 is a left side view of the chair control housing of FIG. 1;

FIG. 5 is a front view of the chair control housing of FIG. 1;

FIG. 6 is a rear view of the chair control housing of FIG. 1; and,

FIG. 7 is a top view of the chair control housing of FIG. 1. The broken lines shown in FIG. 1 are for environmental purposes only. The broken lines which define boundary line edges of the design are shown in FIGS. 1 through 7. All broken lines form no part of the claimed design.
